UNITED STATES PATENT OFFICE.

BENJAMIN K. VAN NORTWICK, OF UNDERCLIFF, NEW JERSEY.

DESIGN FOR A CASING FOR STEAM-JET BLOWERS.

SPECIFICATION forming part of Design No. 28,745, dated May 31, 1898.

Application filed November 17, 1897. Serial No. 658,370. Term of patent 7 years.

To all whom it may concern:

Be it known that I, BENJAMIN K. VAN NORTWICK, a citizen of the United States, residing at Undercliff, in the county of Bergen and State of New Jersey, have invented and produced a new and original Design for a Casing for Steam-Jet Blowers, of which the following is a specification, reference being had to the accompanying drawings, in which—

Figure 1 is a plan view of my new design, and Fig. 2 a view in side elevation.

As shown in the drawings, the leading or material feature of my design for a casing for steam-jet blowers consists of a circular central cylindrical body portion A, in the center of which is formed or produced a circular nozzle-piece F, presenting a circumferential milled edge, as shown, and from the body is extended radially a round extension G, having a beaded and rounded end, as shown. From the perimeter of the circular body portion A

are produced and radially extended a plurality of rounded pipe-arms B, terminating in circular nozzle-pieces D, depending vertically at the outer ends of the pipe-arms, the said nozzle-pieces in side or vertical contour being made up of upper and lower cylindrical portions of different diameters with inclined or conical middle portions, and the lower and smaller part terminating in tapering formations, as shown in Fig. 2 of the drawings. The heads of the nozzle-pieces D are circular and have milled edges, as shown.

What I claim is—

The design for a casing for steam-jet blowers, substantially as herein shown and described.

BENJAMIN K. VAN NORTWICK.
